UNITED STATES PATENT OFFICE.

JACQUES BOTELLA, OF PARIS, FRANCE.

COLLAPSIBLE AUTOMOBILE TOP.

Application filed March 8, 1922. Serial No. 542,092.

To all whom it may concern:

Be it known that I, JACQUES BOTELLA, a citizen of the French Republic, residing at 3 Rue Georges Ville, Paris, France, have 5 invented new and useful Improvements in Collapsible Automobile Tops, of which the following is the specification.

All the carriage bodies with hoods for motor cars of the cabriolet, landaulet, torpedo cabriolet-type, are provided with hoods which fold down on the elbow rests of the rear seat in various ways, form projections more or less unsightly in the line of the car and presenting the serious inconvenience 10 of offering a great resistance to the air by the surface of the hood which extends beyond the back of the car.

This invention has for its object a hood which, folding down outside the elbow rests 20 and back of the car, allows a motor cabriolet to be transformed into an open torpedo having absolutely sportive lines, offering the maximum of elegance and the minimum of resistance to the air.

25 This hood is characterized in that the uprights supporting the hoops move away from the elbow rests when they are folded down, coming, as in an ordinary torpedo, outside and below the level of the elbow 30 rests, clearing entirely the latter and the back of the car. This operation can be obtained by pulling the uprights outwardly, these latter being mounted in a slide, or automatically by means of two helical inclines 35 acting at the central points of rotation, or by any other mechanical device.

40 A form of construction of a hood in accordance with the present invention is illustrated by way of example in the accompanying drawing in which:

Fig. 1 is a perspective view showing the whole of the skeleton work of the hood in service position (cabriolet).

45 Fig. 2 is a view showing this skeleton work put down (torpedo).

Fig. 3 is a partial plan view showing the position of the uprights and hoops of the hood when brought down.

50 Fig. 4 is a perspective view showing the uprights guiding the front glass and the bridge covering its housing half folded down, as well, as the covering of the door glasses.

55 Fig. 5 is a vertical section, on an enlarged scale, through a plane containing the helical incline automatically guiding, through the

folding down or rotary movement, the pivotal axis of the hood.

The links 1 which are secured to the uprights of the hood are mounted on an axis 60 2 capable of rotating in a bearing 3 secured between the thickness of the side walls and the lining of the carriage body, a little way below the elbow rests against the upright 65 of the door. This axis 2 is so arranged that it can be subjected to a translation according to its axis, outwardly to the car when the uprights secured to the links 1 are brought down, that is to say when it is desired to fold down the hood for opening the 70 car.

By way of example, this double movement of rotation and of translation of the axes 2 is realized in the following manner:

The axis 2 carries a cylindrical key 4 at 75 right angles to its axis which can move in four corresponding helical grooves provided, two in the bearings 3, two in a concentric wall of a sheet-iron cylinder 3¹ secured in the side-wall of the carriage body. 80

When the link 1 rotates in the direction of the arrow (Fig. 1) the axis 2 slides in its bearing, moving away from the longitudinal axis of the car. It takes back its initial position when the link 1 is brought again 85 forwardly so that the hood upright 10 which it conducts, is vertical. This upright 10 is broken at its upper part by a hinge 11. By means of this arrangement, the skeleton work of the hood covered with leather in 90 the known manner, can be folded and arranged outwardly and below the elbow rests, as shown in Fig. 2.

The hoop 6 holding the leather according to the shape of the rear of the hood, is 95 broken at the points *a* and *a*¹ (Fig. 3) by two hinges the axes of which are vertically arranged, so as to be able to follow the spacing apart movement of the uprights 10 during the lowering operation. Moreover, the arms of this hoop are broken at the point 15 by a horizontal axis, and at the point 17 for allowing them to fold back when the hood is lowered down, in order that they 100 may not extend beyond the alignment of the uprights 10.

For rendering this operation automatic, with the raising of the hood, a small link 14 hinged at both ends compels the arms of 105 the hoop 6 to unfold by the pulling of the leather on the part 16.

The front of the hood covering the top

of the doors operates according to the known systems and locks itself on the uprights 7 of the front glass (Fig. 4).

The whole of the hood is held rigid by 5 two rule joints 12 hinged on the top of the uprights and the hood support 20.

The front glass disappears in the back of the front seat as well as the uprights 7 which serve as vertical supports therefor 10 and the upper spacing cross bar 9 on which is placed a sheet iron or wooden bridge 13 completely hiding the passage of the glass when it is lowered down. The uprights 7 are connected to the spacing bar 9 by two 15 links 8 hinged at both ends in order to raise the whole by pulling vertically on the spacing bar 9.

When the frame formed by the two uprights and the spacing bar has been rendered rigid by locking it to the hood by a fastening device arranged at the upper part of the uprights, the glass is fitted up by 20 the systems currently employed.

The glasses of the doors move down in 25 the hollow of the doors with their metal uprights (according to the known system) and the passages are covered by piano hinges 15' (Fig. 4).

For lowering the hood, the front of the 30 latter is first disengaged from the front uprights, then one of the rule joints is closed (the other being combined with the first one by a common axis passing through the car along the back) and the whole folds back 35 outside the carriage body. For preventing the dust from entering in the members of the hood, the whole is enclosed in a cover as usual.

The combination of the three glasses for 40 constituting a hinged window can be used when the hood is folded down.

The uprights of the front glass disappear as shown in Fig. 2.

What I claim as my invention and desire 45 to secure by Letters Patent is:

1. In a hood for motor vehicle, a front hoop supporting the hood and the ends of which are connected by pivoted links to two uprights about midway of the height of 50 these uprights, said uprights being pivoted at their lower ends to the rear face of the back of the driver seat in order to be capable of being brought down parallel to the said rear face, rear door uprights the lower 55 ends of which rest on the elbow rests and are connected with extensions movable about an axis at right angles to the side faces of the carriage body,—means for displacing the axis of rotation of the said extension in 60 order to allow the rear door uprights to be brought down outside the carriage and below the plane of the elbow rests,—and means for connecting the skeleton work of the hood to the rear hoop supporting the latter, so as 65 to permit the spacing of the said skeleton

work at the same time as that of the rear door uprights.

2. In a hood for motor vehicles, a front hoop supporting the hood and carried by two front door uprights pivoted at their 70 lower end on the rear face of the back of the driver seat so as to be capable of being brought down horizontally in a plane parallel to the said rear face, links connecting the ends of the front hoop to the middle of the front door uprights for causing the hoop to come behind the back of the driver seat of which it is capable of forming the upper face;—rear door uprights the upper ends of which are connected to the front hoop by 80 bridges made of two jointed parts hooking on the ends of the front hoop, the two parts of the said bridges being capable of folding on each other and on the rear door uprights, supporting levers secured at the lower end 85 of the rear door uprights and connected with an axis pivoting in a socket secured in the thickness of the carriage body, the said axis being slidale relatively to the socket by means of a finger guided in a helical 90 groove, the rear door uprights resting on the upper face of the elbow rests when the hood is raised and coming outside the carriage body and below the plane of the elbow rests when the hood is folded, a rear bow for the 95 hood hingedly connected to the rear ends of two lateral jointed links whose other ends are pivoted to the rear door uprights, at about the central portion of the height of these latter, and struts having their upper ends pivotally connected to the rear door uprights and their lower ends pivoted on a common axis attached transversely at the rear of the carriage body and intended to 100 synchronize the movement of each of the lateral portions of the frame of the hood.

3. The combination with a vehicle tonneau having a driver's seat of uprights movable toward and away from said seat and adapted in lowered position to be concealed by 110 said seat, a front hood bow operatively connected with said uprights and adapted to be lowered with the uprights and to align with the rear portion of said seat, rear uprights having lower extensions, axially movable 115 pivot pins arranged transversely to the longitudinal axis of the tonneau and connected to said tonneau and said extensions, an intermediate bow having its ends pivotally connected to said rear uprights in such manner as to permit the lower ends of said uprights to move with said pivot pins toward and away from the longitudinal axis of the tonneau, a rear bow, links connecting the 120 rear bow to the rear uprights, pivots connecting said links to the rear bow and capable of permitting the forward ends of said links to move laterally with the rear uprights, and hinged struts pivotally connected 125 to the rear uprights and to the tonneau.

4. The combination with a vehicle tonneau having a driver's seat, of uprights connected to the tonneau and capable of movement toward and away from the latter, a front bow associated with said uprights, rear uprights having extensions at their lower ends, axially movable pivot pins connecting said extensions to said tonneau, an intermediate bow, means pivotally connecting the intermediate bow to the rear uprights and capable of permitting the lower ends of the uprights to move toward and away from said tonneau, a rear bow, jointed links having their front ends pivotally connected to the rear uprights, means pivotally connecting the rear ends of the jointed links to the rear bow and capable of permitting the forward ends of said links to move toward and away from the longitudinal axis of the tonneau, and hinged struts having their ends connected to said rear uprights and said tonneau.
5. A combination as claimed in claim 4 including links having their rear ends pivotally connected to the jointed links and their forward ends pivotally connected to said uprights.
6. A combination as claimed in claim 4, including jointed bridge members connecting the upper ends of said rear uprights to the upper ends of the front uprights.

In testimony whereof I have signed my name to this specification.

JACQUES BOTELLA.
